UNITED STATES PATENT OFFICE.

HEMAN E. OWENS, OF WEST CLARKSVILLE, NEW YORK.

ROTARY HARROW.

1,270,317.

Specification of Letters Patent. Patented June 25, 1918.

Application filed February 18, 1918. Serial No. 217,876.

To all whom it may concern:

Be it known that I, HEMAN E. OWENS, a citizen of the United States, residing at West Clarksville, in the county of Allegany 5 and State of New York, have invented certain new and useful Improvements in Rotary Harrows, of which the following is a specification.

This invention relates to agricultural implements, and more particularly to rotary harrows or pulverizers.

The object of the invention is to provide a machine of this character so constructed as to efficiently pulverize the plowed ground 15 over which it passes and which has means to prevent breakage of the pulverizing implements when obstructions are encountered.

Another object is to provide a simply 20 construction and efficient machine of this character having a rotary drum composed of sections held yieldably together to provide a flexible periphery for the drum.

With the foregoing and other objects in 25 view, which will appear as the description proceeds, the invention resides in the combination and arrangement of parts and in the details of construction hereinafter described and claimed, it being understood 30 that changes in the precise embodiment of the invention herein disclosed may be made within the scope of what is claimed without departing from the spirit of the invention.

35 In the accompanying drawings:—

Figure 1 represents a side elevation of a harrow constructed in accordance with this invention,

Fig. 2 is a plan view thereof with parts 40 broken out,

Fig. 3 is a transverse vertical section taken on line 3—3 of Fig. 2,

Fig. 4 is a detail perspective view of a portion of the flexible drum,

Fig. 5 is a similar view of a portion of 45 one of the adjustable connections for the sprocket wheels,

Fig. 6 is a side elevation of a slightly modified form of the invention, and

Fig. 7 is a plan view of the frame thereof.

In the embodiment illustrated in Figs. 1 to 5, a wheel supported structure is shown comprising a pair of ground wheels 1 between which is fixedly mounted, on the 55 axle 2 which connects the wheels, a substantially rectangular U-shaped horizontally

disposed supporting frame 3 having a suitably braced tongue 4 connected with the cross bar 4' thereof, the free ends of the arms of said frame being engaged with 60 axle 2.

An auxiliary frame is mounted within frame 3 and comprises two side bars as 5 disposed on opposite sides of axle 2. The opposite ends of these side bars 5 are 65 bifurcated to receive sprocket wheels 7 and 8 which are slidable on the side bars in a manner and for a purpose hereinafter to be described.

At each side of the machine adjacent the 70 ground wheels 1 are sprocket wheel supporting members here shown in the form of arms or bars 9 which radiate from axle 2 and are connected by braces 10; four of these arms 9 are here shown disposed dia- 75 metrically opposite each other and between the two upper arms 9 is disposed another arm 9' there being no arm arranged opposite arm 9' for a reason presently to be described. These arms 9 and 9' are arranged 80 in the same plane with the side bars 5 so that the sprocket wheel 12 carried by said bars and those 7 and 8 carried by said bars will be arranged in the same plane and adapted to support sprocket chains as 11, 85 one of which is arranged at each side of the machine as is shown clearly in Figs. 2 and 3.

Sprocket wheels 12 are mounted to slide longitudinally on the arms 9 similar to the wheels 7 and 8 which are mounted on the 90 side bars 5 to adapt said wheels to be properly adjusted in relation to the chains 11 which they support and to which they impart motion. These wheels 7 and 8 are preferably each mounted in a bifurcated sleeve 95 13 as shown in detail in Fig. 5, the wheel being disposed between the bifurcations of the sleeve and the inner end of said sleeve mounted to slide on one end of the bar 5. The connection between the arms 9 and their 100 sprocket wheels is the same as that between bars 5 and the wheels 7 and 8. A link 14 is connected at one end with sleeve 13, and at its other end with a lever 18 which is fulcrumed at one end on bar 5. A segmental 105 rack 16 is also secured to bar 5 adjacent the lever 18 and is designed to be engaged by a spring dog carried by said lever for locking it in an adjusted position. It will thus be seen that the sleeve 13 which carries the 110 sprocket wheel may be adjusted longitudinally on the arm or bar on which it is mount-

ed by simply disengaging the spring dog on lever 18 and through the actuation of the lever positioning the sleeve at the desired point so that the sprocket wheel carried thereby may be moved toward or away from the chain with which it is to be engaged.

5 The arm or bar 9' is the only sprocket carrying member which is provided with no means for adjusting its sprocket as it is not deemed necessary to employ such means in 10 connection with this arm.

The two sleeves which carry the sprockets 7 and 8 are connected for simultaneous actuation by means of a rod 17, one end of which 15 is connected with one end of a lever 18 fulcrumed intermediately of its ends on side bar 5, the other end of said rod 17 is connected with the sleeve 13 which carries sprocket 8 as is shown clearly in Fig. 1.

20 This lever 18 is connected with sprocket 7 by means of a link 14 as heretofore described, and it will thus be seen by the actuation of this lever the two sprockets 7 and 8 will be simultaneously moved toward or away from 25 each other according to the direction in which the said lever is actuated. It is sometimes found desirable to move the sprockets 7 and 8 outwardly to cause chain 11 with 30 which they are engaged at diametrically opposite points to be moved outwardly in diametrically opposite directions and thereby elevate the lower portion of the chain to disengage the teeth carried thereby from the surface over which the machine is passing, 35 which is necessary when passing from field to field. This upward movement of the chain 11 may also be employed to regulate the depth which the teeth are designed to engage the earth being harrowed.

40 The chains 11 which are disposed at opposite sides of the machine are connected by a plurality of peripherally spaced cross bars or arms 19 any desired number of which may be employed. Each of these bars 19 carries a plurality of longitudinally spaced teeth 20 any desired number of which may be used. These teeth 20 are preferably detachably mounted on bars 19 by any suitable means, nuts 21 being here shown for this 45 purpose so that should one of the teeth become broken it may be readily replaced. Carried by the bars 19 and spaced laterally and outwardly therefrom are guide bars 22 through which the teeth 20 extend and are braced thereby.

55 These teeth carrying bars are yieldably connected by means of coiled springs 23 as is shown clearly in Fig. 4 and when so connected provide a yieldable or flexible drum having teeth radiating therefrom and which is designed to engage and pulverize the earth over which the machine is caused to travel.

Motion is imparted to this flexible drum 60 by means of cog wheels 24, two of which are

preferably employed although not necessarily, and which are carried by shafts 25 on which two of the upper sprocket wheels 12 are mounted, said shafts extending from one side of the machine to the other, 70 and connecting the corresponding sprocket wheels at opposite sides thereof. These cog wheels 24 mesh with an annular toothed gear 26 which is here shown in the form of an internal gear while in Fig. 6 an external gear is shown. This gear is fixed to the inner face of one of the ground wheels 1, being here shown mounted on the wheel at the left hand side of the machine.

Any suitable means may be provided for 80 throwing these cog wheels into and out of mesh with the gear 26 so that the drum may be operated or not during the travel of the machine at the will of the operator.

It is to be understood that any desired 85 number of sprocket gears may be employed, seven being here shown and arranged as shown in Fig. 1 with sufficient space left between the two lower wheels to provide for the positioning at this point of a spring 90 cushioning frame which is designed to engage the lower portion of the drum where it comes in contact with the ground when in use, and which is designed to permit the drum to yield at this point when it encounters 95 obstructions such as stones and the like. This spring cushioned frame consists as here shown of a pair of depending rods as 27 which depend from frame 3 at opposite sides of the machine (see Fig. 1) and which are 100 connected at their lower ends by a rod 28 which forms a pintle for arcuate peripherally extending bars or plates 29, one end of which is provided with a knuckle or eye 105 for pivotal engagement with said rod 28. The rods 27 which depend from frame 3 terminate at their lower ends at a point spaced sufficiently from the chains 11 to provide ample space between the said ends and said chains of another arcuate bar 31 which 110 is also pivotally connected at one end with rod 28 and between which and the bar 29 is arranged coiled springs 32, three being here shown, but obviously any desired number may be employed. The bars 29 and 31 extend in a direction peripherally of the drum and the free end of the bar 29 is connected with an upwardly extending rod or bar 33 which passes up through one of the side bars 5 and is connected at its upper end with a 120 bell crank lever 34 which is fulcrumed on the side bar 5 and is provided with the usual spring pressed dog 35 which is adapted to engage with the teeth of a segmental rack 36 for locking the lever in adjusted position. 125

The free end of bar 31 is also connected with an upwardly extending bar 37 which is provided with guides 38 here shown in the form of loops through which bar 33 passes on which said bar 37 is designed to slide. 130

It will be understood that the object of this spring cushion is to permit the endless chain carrying the teeth 20 to yield and conform to the shape of the ground over which the machine is drawn so that when said teeth come in contact with any solid resisting substance they will not be broken. It will also be seen that the extent of yielding of the drum at this point may be controlled by the number of coiled springs 32 employed or by the adjustment of the lever 34 to raise or lower the cushion frame according to the extent it is desired that said chain shall yield. If desired, a swiveled caster wheel 40 may be mounted at the front of the frame preferably at a point underneath the junction of the tongue with the hounds. This wheel is designed to support the machine and to assist the turning thereof and to prevent the weight and jar from being received by the necks of the horses, when horses are employed for drawing the machine over the earth.

It is to be understood that while this machine is shown with a tongue provided for the use of horses that it may be equally well connected with a tractor operated by motive power in any suitable manner.

In the operation of the machine when it is drawn forward over the surface to be pulverized or harrowed, the rotation of the wheels 1 will operate through the crown gear 26 carried by one of said wheels to impart motion through the cog wheels 24 to the sprockets 12 mounted on the shafts 25 thereof, and thereby drive the sprocket chains 11 and cause the teeth 20 carried thereby to be brought into operative engagement with the earth over which the machine is passing, the spring cushion frame at the lower portion of the drum operating to force the teeth yieldably outward into the earth when they reach a point above the ground to be pulverized as is shown clearly in Fig. 1 and permits them to retract when an obstruction is encountered. It is understood that this frame has first been adjusted by the means above described to adapt the teeth carried by the drum to engage the surface being pulverized any desired depth.

The annular gear 26 shown in Figs. 1 to 5 will operate to turn the chains 11 rearwardly, while the external gears 26' shown in Fig. 6 will operate to turn them in the opposite direction and either form may be employed, it being preferable to turn the chains forwardly in order that the lumps of earth to be pulverized may be the second time subjected to the action of the teeth 20.

In the form shown in Figs. 6 and 7, the harrow is made double, two drums being employed instead of one as shown in the other figures. These drums are constructed exactly alike and are made exactly like the drums shown in Figs. 1 to 5 and hereinbe-

fore described, hence it is not deemed necessary to again describe them. These drums are mounted side by side in the frame shown in Fig. 7 which is similar to the frame 3 of the other figures except that it is made wider to accommodate the two drums and has central partitions 41. This frame is mounted on an axle 2 which has rods 42 on each side thereof for bracing and strengthening it. This double form of frame not only lengthens the harrow but strengthens it and is especially designed for use by machines to be drawn by tractors. This frame has arranged between the side members thereof and the middle partition 41 in each compartment, bars 43 which have open slots 44 at their free ends to receive the sliding boxes, sprocket wheels, etc., and correspond to the bars 9 in the form shown in Figs. 1 to 5.

From the foregoing description taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

I claim:—

1. In a rotary harrow, a wheeled supporting structure, a drum mounted therein, a flexible endless member mounted to move around said drum, outwardly projecting teeth carried by said member, means connected to actuate said endless member, and spring cushioned means for projecting the teeth of said endless member into operative position for engaging the ground.

2. In a rotary harrow, a wheeled supporting structure, a drum mounted therein, a flexible endless member mounted to move around said drum, outwardly projecting teeth carried by said member, means connected to actuate said endless member, and spring cushioned means mounted to slide vertically directly over the point of engagement of the endless member with the ground for projecting the teeth of said endless member into operative position for engaging the ground.

3. In a rotary harrow, a wheeled supporting structure, a drum mounted therein, a flexible endless member mounted to move around said drum, outwardly projecting teeth carried by said member, means connected to actuate said endless member, spring cushioned means mounted to slide vertically directly over the point of engagement of the endless member with the ground for projecting the teeth of said endless mem-

- 41
- ber into operative position for engaging ground, and means under the control of the operator for raising and lowering said projecting means to prevent engagement of the 5 teeth of said member with the ground to vary the extent of their engagement.
4. In a rotary harrow, a wheeled supporting structure, a drum mounted therein, a flexible endless member mounted to move 10 around said drum, outwardly projecting teeth carried by said member, means connected to actuate said endless member, and means for projecting the teeth of said endless member into operative position for en- 15 gaging ground, said projecting means comprising two members, one slideable relatively to the other and having coiled springs positioned between them, the slideable member being arranged outside and yieldable in- 20 wardly.
5. In a rotary harrow, a wheeled supporting structure, a drum mounted therein, a flexible endless member mounted to move around said drum, outwardly projecting 25 teeth carried by said member, means connected to actuate said endless member, means for projecting the teeth of said endless member into operative position for engaging the ground, said projecting means comprising 30 two members, one slideable on the other and having coiled springs positioned between them, and means for raising said members to prevent engagement of said teeth with the ground.
6. In a rotary harrow, a supporting frame, ground wheels supporting said frame, a skeleton drum fixedly mounted therein and including a plurality of radially adjustable sprocket wheels, endless sprocket chains passing over said wheels, toothed rods 40 connecting said chains, and a connection between one of said ground wheels and said sprocket wheels whereby the chains are driven by the turning of the ground wheels. 45
7. In a rotary harrow, a supporting frame, ground wheels supporting said frame, a skeleton drum fixedly mounted therein and including fixed end members, a plurality of shafts connecting and extending through said members, cogs on said projecting shaft ends, a gear carried by one of said ground wheels and with which said cogs mesh whereby motion is imparted to said shafts, an endless flexible member 50 encompassing said drum and carrying pulverizing elements, connections between said flexible member and shafts whereby said member is moved around said drum, and means for projecting said flexible member to cause the teeth thereof to engage the ground. 55

In testimony whereof I affix my signature in presence of two witnesses.

HEMAN E. OWENS.
